UNITED STATES PATENT OFFICE.

ALFRED BERTHOLD ANDREAS FICH, OF COPENHAGEN, DENMARK.

METAL CONTAINER AND THE LIKE.

1,427,152.

Specification of Letters Patent. Patented Aug. 29, 1922.

Application filed September 20, 1920. Serial No. 411,490.

To all whom it may concern:

Be it known that I, ALFRED BERTHOLD ANDREAS FICH, subject of the King of Denmark, residing at Islands Brygge 11, Copenhagen, Denmark, have invented new and useful Improvements Relating to Metal Containers and the like, of which the following is a specification.

As it is well known, it is common to open tin cans for preserved goods and the like by tearing open the cover of the can, or the can itself, either with or without the use of a special key, and the tearing is rendered possible by reason of the material of the can being weakened in certain lines along which the tearing is intended to be effected.

It is well known, however, that tear frequently fails to follow the weakened lines but will diverge therefrom before the operation is finished in satisfactory manner. When such improper tearing results, it is frequently necessary to mutilate the contents of the same in removing it.

According to the present invention, the weakening of the said lines in tin covers is effected by rendering the material brittle along the said lines. And further, according to this invention the material is compressed instead of being scratched or cut down in thickness as heretofore. By this compression, which is one of the distinguishing features of the present invention, the material which is usually soft becomes brittle, as above stated, and experience has shown that if the material is reduced to a suitable minimum thickness, for instance 0.06 to 0.1 millimeter, then the tin cans whose material is weakened in this manner will be exceedingly easy to open, as the percentage of error, that is to say the number of cans in which the process of opening fails, is less than one per cent of the total number of cans. The principal reason for this is that the weakening produced by the compression is extremely uniform, and that it is very much easier to produce a uniform thickness of metal all along the weakened lines by the said compression than by means of scratching or cutting tools, which practically all make an incision of definite depth in the material. Differences in the thickness and hardness of the material conse-

quently cause differences in the thickness of metal in the weakened portions, for instance by the scratching or cutting edge being bent or deflected sideways, and as the thickness of material in the weakened portions is very small in itself, casual variations amounting to 0.03 to 0.05 millimeter will often have the effect that the tearing will be unsuccessful.

The production of the weakened lines is effected in known manner by the tinplate being pressed between two dies, one of which has its working surface shaped as a thin, hardened steel edge. According to the invention this steel edge, whose shape is exactly similar to the lines to be weakened, is blunt.

The drawing represents one embodiment of the invention,

Fig. 1 showing the upper die and

Fig. 2 the lower die in a press adapted to perform the above mentioned operation, while

Fig. 3 shows the bottom die in top view, and

Figs. 4 and 5, respectively, show a top view and a longitudinal section of a modified construction of the die with a steel strip inserted.

The upper die consists of a hardened stopping die member 1 which is shaped as a ring and encircles a plate 2 which is held, in suitable known manner, in the die holder 85 3. The die plate 2 supports a form plate 4 whose lower face is shaped according to the cover or the like which is to be treated in the press, so that during the pressing operation the cover is contained in a space 90 between this plate 4 and a corresponding plate 5 in the bottom die. The said plate 5 is encircled by a ring 6 which is so much larger than the plate 5 that a narrow slot is formed between the latter and the said 95 ring, so that a hardened steel strip 7 may be driven down into this slot and held in position there. The height of the ring 6 is such that the steel strip 7 projects slightly, for instance 0.25 to 0.3 millimeter beyond 100 the top surface of the ring, and the ring 1 in the top die is of such height that when the top die is moved down towards the bottom die, the motion of the top die will

be stopped by the said ring 1 meeting a fixed stop 8 on the bottom die, so that there will be left, between the blunt top edge of the steel strip 7 and the working surface 5 of the die plate 2 in the top die, a very small space equaling the thickness of metal in the weakened grooves in the treated tinplate. The rings 1 and 6, the die plate 2 and the steel strip 7 must be ground in 10 such a manner that the opposite faces on the rings 1 and 6, respectively, and on the strip 7 and the die plate 2 are perfectly flat and parallel. The tinplate or cover to be treated is placed on the disc 5 in such a 15 manner that it covers the steel strip 7 whose shape corresponds exactly to the shape of the lines which are to be weakened in the tinplate.

The top die is now moved down towards 20 the bottom die and, as mentioned above, the latter will be stopped in such a position that there will be left, between the top surface of the strip 7 and the bottom face 9 of the plate 2 a definitely determined slight 25 space which determines the thickness of metal in the lines weakened thereby in the tinplate.

It is not necessary to take any kind of 30 precautions in order to avoid the possibility of unevenness in the weakening of the covers. The press works with absolute accuracy, without regard to the thickness of the material used, and the life of one single 35 steel strip is exceedingly long, so that one single steel strip may be used for several years during continuous operation of the press.

The rings 1 and 6 and the die plates 5 and 2 must be of a shape depending on the 40 shape of the material concerned which is to be treated in the press, but may otherwise be formed in any suitable manner. The individual parts must be fitted with very great accuracy, but when they are once fitted up, the press may work for a long period 45 without any kind of adjustment or replacement of worn parts. The only member which may possibly have to be replaced is the steel strip 7, which is easy to detach and replace by a new one, and the cost of 50 which is exceedingly slight in comparison with the costs heretofore incurred in repairing presses of the present kind, when the working tools have been damaged.

If it be desired to increase the weakening, 55 some paper or metal foil, of a thickness corresponding to the increase of the compression, must be inserted between the die plate 2 and the pressing head or die holder 3 and, if it be desired to reduce the depth of the 60 weakening, paper or metal foil of a thickness corresponding to the decrease must be inserted between the ring 1 and the pressing head 3.

The die into which the strip 7 is inserted 65 may obviously also be used as the top die instead of as the bottom die.

In the construction shown in Figs. 4 and 5, the steel strip 7 ends blindly at both ends, the strip being inserted into and passing back and forth through two essentially parallel slots converging at one end in such a manner that when for instance a tinplate cover is being weakened, there will be impressed therein two mainly parallel weakened 75 lines converging at one end.

Having now particularly described and ascertained the nature of my said invention and in what manner the same is to be performed, I declare that what I claim is:— 80

1. An apparatus for producing weakened lines in metal tin plate comprising a die; and an edgewise disposed steel strip inserted in said die, said strip having a working edge rectangular throughout and projecting beyond the pressing face of said die, said rectangular working edge being entirely free from any adjacent members so as to insure that the entire edge will act upon the metal plate worked upon and will exert a compressing action, as distinguished from a displacing action, along the lines to be weakened in said plate. 85

2. An apparatus for producing weakened lines in metal plates comprising a die, said strip having a working edge rectangular throughout and projecting beyond said die and entirely free from any adjacent members; a hardened steel member engaging the rear edge of said steel strip; a ring encircling the steel strip and securing the latter to the hardened steel member; and a plate encircling said ring, there being between said ring and said plate a narrow slot to receive the steel strip. 95

3. An apparatus for producing weakened lines in metal plates comprising a die, said strip having a working edge rectangular throughout and projecting beyond said die and entirely free from any adjacent members; a hardened steel member engaging the rear edge of said steel strip; a ring encircling the steel strip and securing the latter to the hardened steel member; and a plate encircling said ring, there being between said ring and said plate a narrow slot to receive the steel strip, said plate having a perforation in order to facilitate the separation of the ring and the plate. 100

4. An apparatus for forming closures for 110 metal containers comprising a die and a companion die member; means to limit the movement of said die and die member toward each other so that the major portions of the die and die member will not compress the metal worked upon; and portions on said die and die member between which the metal worked upon is adapted to be 115

compressed by the relative movement between the die and member, said portions comprising a flat working face adapted to compress the metal without displacing the same in a direction perpendicular to the direction of the compressing force.

5 In witness whereof I have hereunto signed

my name in the presence of two subscribing witnesses.

ALFRED BERTHOLD ANDREAS FICH.
